UNITED STATES PATENT OFFICE.

FRANK T. WIECHERT, OF BELLEVUE, OHIO.

FOUNTAIN-FAUCET.

1,167,959.

Specification of Letters Patent. Patented Jan. 11, 1916.

Application filed October 8, 1914. Serial No. 865,683.

To all whom it may concern:

Be it known that I, FRANK T. WIECHERT, a citizen of the United States, residing at Bellevue, in the county of Huron and State 5 of Ohio, have invented certain new and useful Improvements in Fountain-Faucets, of which the following is a specification.

My invention relates to improvements in fountain faucets, the present embodiment of 10 the invention being particularly designed and adapted for use in drawing or dispensing carbonated water in connection with soda fountains.

The primary object of the invention is to 15 provide a generally improved faucet of this class which will be exceedingly simple in construction, cheap of manufacture, and efficient in use.

A further object is the provision of a 20 fountain or dispensing faucet which may be operated and controlled with exceedingly great ease and convenience and in which the various parts are so arranged and disposed as to reduce liability to breakage or disarrangement to a minimum.

A still further object is the provision of what may be termed a "double acting" fountain faucet, that is to say,—one in which the operating handle is adapted to perform its 30 functions by either a rearward or forward movement on its pivot.

With the above mentioned and other ends in view, the invention consists in the novel construction, arrangement, and combination 35 of parts, hereinafter described, illustrated in one of its embodiments in the accompanying drawings, and particularly pointed out in the appended claims.

Referring to the drawings, forming a 40 part of this specification, Figure 1, is a side elevation of the improved fountain faucet in its normal or closed position. Fig. 2, an enlarged central longitudinal sectional view of the faucet body, the parts being shown 45 in closed position. Fig. 3, a front elevation of the improved faucet on the scale shown in Fig. 1.

Similar numerals of reference designate like parts throughout all the figures of the 50 drawings.

The improved fountain faucet comprises a stationary valve body 1, in the present instance, screw threaded upon a supply pipe or stem 2, said valve body being provided 55 with oppositely disposed or upper and lower valve chambers 3 and 4, respectively. The

upper and lower valve chambers communicate with each other through the medium of an intermediate valve opening or reducing passage 5, the latter having oppositely disposed annular valve seats 5^a, and as a means of conveniently forming said valve opening 5, and valve seats 5^a, as well as of assembling the parts, said valve body 1, is preferably provided with a second section 1^a, which latter is screw threaded upon the lower end of the body or section 1, and in the present instance, forms the lower valve chamber 4. The second section 1^a, is preferably screw threaded at its lower end similar to the part 70 or section 1, and is provided with a depending cap 6, having an opening 6^a, communicating with the lower valve chamber 4. If desired, suitable packing gaskets 7, may be interposed between the parts 1, 1^a, and 6, as 75 shown. The supply pipe or stem 2, is provided with a suitable supply opening or port 2^a, communicating with a supply port or passage 3^a, leading to the upper valve chamber 3. 80

As a means of opening and closing communication between the valve chambers 3 and 4, as well as regulating the supply of liquid to and through the discharge stem or bib portion of the faucet a movable valve 85 stem 8, is provided, said stem, in the present instance, comprising upper and lower members 8 and 8^a, respectively, said valve stem extending through the valve opening or passage 5, and carrying upper and lower valve 90 members 9 and 9^a, in the chambers 3 and 4, being adapted to be seated upon the valve seats 5^a, whereby upon the movements of the valve stem said passage 5, is adapted to be opened and closed thereby opening and 95 closing communication between the chambers 3 and 4. The valves 9 and 9^a, are preferably formed of suitable resilient material such as rubber or the like, and, in the present instance, are mounted upon attaching 100 disks or flanges carried by the members 8 and 8^a, of the valve stem.

As a means of providing for the drawing of a small fountain or pencil stream as desired in fountain faucets of this class, the 105 valve stem is provided with a centrally located longitudinally extending passage 10, said passage 10, in the present instance, being formed in the lower member 8^a, of the valve stem and being provided with a lateral 110 inlet port 10^a, communicating with the intermediate valve opening 5, so that when the

valve stem is elevated, by the mechanism hereinafter described, to close the passage 5, through the closure of the lower valve 9^a, said inlet port 10^a, only communicates with 5 the passage 5, and upper valve chamber 3, thereby causing a small fountain or pencil stream to issue from the faucet portion of the improved faucet. The valve member 8^a, is preferably screw threaded at its upper 10 end to connect with a similarly threaded opening in the lower end of the stem member 8, and the relative distance between the valve members 9 and 9^a, may be regulated through the medium of washer members 11, 15 it being apparent that by elevating or moving the lower stem 8^a, and the valve member 9^a, carried thereby upwardly the opening between said valve member 9^a, and its seat may be regulated thereby regulating the 20 ordinary liquid stream issuing therethrough.

The upper end of the stem 8, is guided in a guide opening 1^b, of the stationary member 1, in its vertical movements, it being observed that an annular passage is formed 25 about such stem which communicates with the supply port or passage 3^a.

As a means of operating or moving the valve stem as well as providing a suitable bib or nozzle, a movable faucet member 12, 30 is provided, said faucet member 12, consisting, in the present instance, of a cylindrical member surrounding the stationary valve body and guided at its upper ends in an annular groove or recess 1^c, (see Fig. 2) of 35 the stationary valve body 1, the lower end of said vertically movable faucet member 12, terminating in a bib or depending nozzle 13, the latter being adapted to support and move the valve stem through the medium of 40 a spider support 14, the lower end of the valve stem being loosely mounted in a suitable opening in the spider 14, and being supported by a shoulder 8^b.

As a means of giving the vertically movable faucet member 12, and the stem and valve members carried thereby, the requisite movements a vertically extending handle 15, is provided, said handle being mounted and fulcrumed upon the stationary valve body 1, 50 through the medium of oppositely disposed fulcrum members 15^a, adapted to coöperate with oppositely disposed beveled or inclined portions 1^d, at the front and rear sides of the valve body, the arms 15^b, of the handle being 55 pivotally secured to opposite sides of the cylindrical portion of the vertically movable faucet member 12, through the medium of pivot screws 16, so that when the handle 15,

is moved either forwardly or rearwardly by the hand of the operator the coöperation of 60 the fulcrumed members 15^a, with the inclined portions 1^d, will cause the faucet member 12, to be correspondingly elevated and the valve members 9 and 9^a, correspondingly moved or operated for controlling the 65 fountain stream through the faucet in an obvious manner and as hereinbefore explained.

From the foregoing description, taken in connection with the accompanying drawings, the operation and advantages of my invention will be readily understood.

Having thus described one of the embodiments of my invention, what I claim and desire to secure by Letters Patent, is,—

1. A fountain faucet, comprising a stationary valve body including a section threaded thereon and having oppositely disposed valve chambers, a movable surrounding cylinder terminating in a nozzle member 80 carrying a hollow valve stem, the latter being removable with the removal of said section and adapted to communicate with one of said valve chambers, valves on said valve stem operating in said valve chambers and 85 adapted to open and close communication between said valve chambers and between one of said valve chambers and said hollow valve stem, and means for operating and regulating the movements of said movable 90 cylinder and nozzle member.

2. A fountain faucet, comprising a stationary valve body having oppositely disposed valve chambers, said valve body including a threaded section forming one of 95 said chambers and provided with oppositely disposed valve seats, a vertically movable surrounding cylinder and nozzle member carrying a liquid discharge valve stem adapted to communicate with one of said 100 valve chambers and provided with oppositely disposed valves operating in said valve chambers and coöperating with said valve seats, and means for operating said vertically movable surrounding cylinder and 105 nozzle member whereby to operate said valves and open and close communication between one of said valve chambers and said liquid discharge stem.

In testimony whereof I have affixed my 110 signature in presence of two witnesses.

FRANK T. WIECHERT.
